TILTABLE MARBLE GAME TABLE

Sandy F. Kraemer, 439 Edgewood Drive,
Colorado Springs, Colo. 80907

Filed Jan. 24, 1968, Ser. No. 10,295

Term of patent 14 years

Int. Cl. D21—01

U.S. Cl. D34—5

FIG. 1.

FIG. 2.

FIG. 3.

FIG. 4.

FIGURE 1 is a top view of the tiltable marble game table showing my new design;

FIGURE 2 is a side elevation thereof, with the opposite side being a mirror image, a portion is shown fragmented to indicate the cylindrical posts that project from the surface of the table;

FIGURE 3 is a bottom view thereof; and,

FIGURE 4 is an end elevation, with the opposite end being a mirror image.

I claim.

The ornamental design for the tiltable marble game table, as shown and described.
